RACING GAME APPARATUS

Arley L. Keith, Washington, D. C.

Application May 27, 1935, Serial No. 23,750

13 Claims. (Cl. 273—86)

This invention relates to new and useful improvements in game apparatus generally, but more particularly of that type wherein racing figures are employed.

5 The principal object of my invention is to provide a race course, and a plurality of racing figures, preferably horses, which are positively moved along the course, and wherein the relative positions of the figures during the race may be controlled by the skill of the players.

10 Another object of the invention is to provide a racing game apparatus of the character described which is simple in construction, cheap to manufacture, and highly amusing in its operation to both young and old players.

15 With these and other objects in view which will more fully appear, the nature of the invention will be more clearly understood by following the description, the appended claims, and the 20 several views illustrated in the accompanying drawings.

In the drawings:

Figure 1 is a top plan view of a racing game apparatus constructed in accordance with my invention.

25 Figure 2 is an enlarged vertical section taken on the line 2—2 of Figure 1.

Figure 3 is a horizontal section taken on the line 3—3 of Figure 2.

30 Figure 4 is an enlarged vertical section taken on the line 4—4 of Figure 1.

Figure 5 is an enlarged elevation showing the operating connection between one of the carriage rails and the associated racing figure support.

35 Figure 6 is a vertical section taken on the line 6—6 of Figure 5.

Figure 7 is a horizontal section taken on the line 7—7 of Figure 2.

40 Figure 8 is a vertical section taken on the line 8—8 of Figure 2.

Figure 9 is an enlarged side elevation, partly in section, showing one of the racing figures, the carriage on which the figure is automatically movable rearwardly, one of the hurdles for the figure, and the manually operable means for rendering the automatic means ineffective.

45 Figure 10 is a vertical cross-sectional view taken on the line 10—10 of Figure 9.

50 Figure 11 is a detail sectional view showing the mounting of one of the racing figures, and

Figure 12 is a detail view showing the adjustable tension for the manually operable control wire.

55 Like reference numerals designate correspond-

ing parts throughout the several figures of the drawings.

As shown in the accompanying drawings, my invention includes a supporting structure or casting A which comprises a circular base 5, a marginal wall 6, and a floor 7 disposed above and in spaced relation to the base and supported by the wall 6. The floor is provided with a plurality of concentric or endless slots or tracks 8, 9, 10 and 11, forming resultant ring portions 12, 13, 14 and 15 which are supported in the plane of the floor by a plurality of arch units 16, 17 and 18 having their legs connected to the floor proper and to said ring portions. The floor is centrally supported, as shown in Figure 2, by means of a post 19 having a base flange 20 mounted on the base 5, the upper end of the post passing through an opening in the floor and being clamped to the floor by screws 21, 21.

A relatively large worm wheel 22 is provided 20 with a rigidly connected hub 23 which extends above and below the wheel and is journaled on the vertical post or bearing 19.

A carriage B is supported below the slots 8 to 11 of the floor to rotate continuously, as distinguished from intermittently. This carriage is sector-shaped and includes front and rear radial channel bars 24, 25 arranged at a suitable angle, and a plurality of concentric track rails 26, 27, 28 and 29 which are rigidly connected to 30 said bars, the inner ends of the bars being directly connected to the hub 23, and the outer ends thereof having rollers 30 journaled thereon and engaging an endless bearing 31 mounted on the wall 6 of the supporting structure A. The 35 track rails are disposed directly under and register with the slots 8 to 11 in the floor. An electric motor 32 is mounted on the base 5 and rotates a worm 33 which is in mesh with the worm wheel 22. Thus, when the motor is running, the carriage B will be continuously rotated in the direction indicated by the arrow in Figures 1 and 7.

The motor is controlled by a switch 34 in the power circuit (not shown). The switch is closed by manual means such as a coin controlled plunger 35 which extends inwardly through the wall 6, and is automatically opened upon the completion of a predetermined number of revolutions of the carriage B. The switch 34, as shown in Figures 2 and 3, is of the pivoted type and is mounted in a block 36 secured to the base 5. The switch includes an upwardly extending radial arm 37 which operates between two laterally extending pins 38, 39 fixed to an actuator bar 40 50 55

arranged in alignment with the plunger 35 and slidably mounted for radial movements in bearing openings formed in spaced posts 41, 42 mounted on the block 36. A star wheel 43 is journaled to rotate about a vertical bearing pin 44 mounted in the block 36, and as illustrated, the wheel is provided with eight teeth. This wheel is disposed below the inner end of the actuator bar 40, and integral with and projecting upwardly from one of the teeth of said wheel is a cam 45 adapted to engage a roller 46 journaled on the inner end of said bar 40 upon each complete rotation of said star wheel and thereby move the actuator bar outwardly to open the switch 34 and thereby stop the carriage B from rotating. A pin 47 depending from the worm wheel 22 is moved by said wheel to successively engage the teeth of the star wheel 43. Thus the pin 47 rotates simultaneously with the carriage B, and immediately following the eighth complete rotation of the carriage the cam 45 will move the actuator bar 40 outwardly to open the switch. In order to retain the actuator bar in either of its extreme positions of movement, I have provided the post 42 with a spring pawl 48 which engages alternately in seats 49, 50 formed in said bar.

It is desirable to start and stop the carriage at the same point along its path of travel and for this purpose I have provided a means which functions immediately following the opening of the switch 34 to lock the carriage against travel, until the lock is released upon closing of the switch. To this end, the upper edge of the switch actuator bar 40 is provided with a cam 51 which extends through the post 42. A vertically movable locking rod 52 is mounted in the post above the cam 51 and is provided on its lower end with a cam-engaging head 53. A coil spring 54 located within the post bears against said head to maintain the latter in yieldable engagement with the cam. Secured to and depending from the front channel bar 24 of the carriage is a spring keeper 55 which is adapted to be engaged by the upper end of the locking rod 52, as shown in Figure 8, when said rod is moved upwardly by the cam 51. The receiving end of the keeper 55 is provided with a downwardly inclined spring finger 55' and the other end with a spaced depending stop finger 56. Thus, when the switch actuator rod 40 is moved outwardly by the cam 45 on the star wheel 43 to open the switch 34, the cam 51 will elevate the locking rod 52 and the upper end thereof will slide past the spring finger 55' of the keeper 55 and will be retained in the space between said finger 55' and the stop 56, thereby retaining the carriage B against movement in either direction.

Respectively mounted for sliding movements along the rails 26, 27, 28 and 29 of the carriage B are racing figures C, D, E, and F such as horses or the like. Each figure is mounted on a horizontal pivot 57 located at the upper end of a sleeve 58 which is slidably mounted on the upper end of a post 59 above the floor 7. A spring 60 is disposed between the sleeve 58 and post 59 and functions to yieldingly retain the figure against upward movement. The post 59 is rigidly connected to the upper end of a flat guide shoe 61 which in turn is rigidly connected to and projects upwardly from a saddle 62 having inner and outer legs 63, 64, the upper end of the guide shoe 61 riding in the associated slot 8, 9, 10 or 11 and serving to thereby stabilize or retain the saddle 62 in a vertical plane. It will thus be

seen that each figure is supported by the associated saddle 62 for movements with the latter along the associated rail, and that the figure is supported above the floor 7 for tilting movements about a horizontal axis and for bodily vertical movements. It will also be observed that the saddle 62 and consequently the associated figures are mounted on the carriage B for independent line movements relative to the carriage, or, in other words, the figures are not only bodily movable along the race course by reason of their being supported on the traveling carriage B but said figures are also capable of being moved either forwardly or backwardly with respect to said carriage, the extent of backward and forward movements of the figures being determined by the distance between the radial channel bars 24 and 25 of the carriage.

Associated with the arch units 16, 17 and 18 are hurdles 65, 66 and 67 respectively, there being four of these hurdles associated with each arch unit and respectively disposed in close proximity to the slots 8, 9, 10 and 11 of the floor 7. Each racing figure carries front and rear rollers 68 and 69 which are adapted to contact the associated hurdle and thereby cause said racing figure to swing about the horizontal pivot 57 and also to be elevated by the hurdle due to the extensible support which consists of the sleeve 58 and post 59. It will be observed in this connection that the spring 60 will maintain the rollers in engagement with the hurdle while passing over the latter.

Separate means for the respective racing figures are provided for automatically moving the racing figures rearwardly along the carriage B during the forward travel of the latter whereby at the end of a predetermined number of revolutions of said carriage all of said racing figures will be moved equally and intermittently from their normal starting positions at the front of the carriage to the extreme rear end of the latter. Separate manually operable means are provided for rendering ineffective said separate automatic means during the movement of said carriage whereby the ultimate positions of the racing figures at the end of the carriage movement will be determined solely by the skill of the players. For these purposes, I have provided the underside of each rail of the carriage B with a rack 70. A gear wheel 71 is located between the legs 63, 64 of each saddle 62 and is fixed to a horizontal shaft 72 journaled in said legs. On the inner end of each shaft 72 is fixed a ratchet wheel 73 having ratchet teeth 74. The gear wheel 71 is formed on its inner face with a concentric recess 75 and mounted in this recess is a coil spring 76, the inner end of the spring being fixed to the shaft 72 as at 77 and the outer end of said spring being fixed to a stud 78 fixed to the inner leg 63 of the saddle 62. Supported on the base 5 of the frame in advance of the hurdles 65, 66 and 67 are three horizontal shafts 79, 80 and 81, and journaled on each of these shafts is a plurality of holding pawls 82, 83, 84, and 85 which are respectively arranged in the paths of movements of the ratchet wheels 73, the shafts 79, 80 and 81 being located in a horizontal plane below said ratchet wheels. Each of these holding pawls is of Y-shaped construction and includes upwardly extending and spaced apart front and rear stop arms 86 and 87 and a depending actuating arm 88. The upper end of the stop arm 86 is disposed above the stop arm 87 and is normally disposed in a horizontal plane 75

which intersects the bottom of the associated ratchet wheel 73. The other arm 87 is normally disposed in a horizontal plane disposed below the ratchet wheel. A back dog 89 is pivotally mounted as at 90 on each saddle 62 for cooperation with the teeth 74 of the associated ratchet wheel 73. Each back dog includes an upwardly extending tail 91 and a spring 92 is interposed between the tail and the guide shoe 61 so as to normally and yieldably retain the dog in engagement with the teeth of the ratchet wheel. Each back dog 89 is provided with a rearwardly and downwardly extending release arm 93, the lower end 94 thereof being disposed in a plane above the shafts 79, 80 and 81 so as to clear the latter during travel of the carriage. These release arms are also disposed in vertical planes located inwardly of the respective pawls so as to clear the latter during travel of the carriage. It will be observed that there is a set of three pawls associated with each racing figure, said three pawls being respectively mounted on the shafts 79, 80 and 81. The three pawls of each set are connected in series by a Bowden wire 95, said wire being connected to the lever arms 88 of the pawls. This Bowden wire is slidably mounted in a tube or casing 96 which is secured to the base 5 by clips 97. The inner ends of these wires 95 are attached to tension rods 98 which extend through openings 99 in a transverse bracket 100 attached to the base 5. The outer end of each rod 98 is threaded and is engaged by a take-up nut 101 and disposed between the bracket 100 and said nut is a coil spring 102. The outer or free ends 35 of the Bowden wires 95 extend outwardly through spaced openings in the wall 6 of the frame and are respectively connected to manually operable hand levers 103 which are pivotally connected as at 104 to brackets 105 attached to the outer face 40 of the wall 6 of the frame. The hand levers 103 are located in spaced relation so as to permit a plurality of players to operate said levers without interference.

In the operation of my invention as thus far described, the carriage will be in a state of rest and the racing figures will be located at the forward end of the carriage. The coin controlled plunger 35 is then actuated and the carriage will be rotated as previously described. After the carriage has been rotated a predetermined number of revolutions, the carriage will be automatically brought to a state of rest as previously described. During the rotation of the carriage a tooth of each ratchet wheel 73 will engage the stop arm 86 of the associated pawl and thereby cause the ratchet to be rotated one step by reason of the carriage moving forwardly. This step rotation of the ratchet will be imparted to the associated gear wheel 71 and as a result the associated figure will be moved rearwardly relative to the carriage. This rotation of the gear wheel imparts a winding motion to the associated coil spring 76 and the back dog 89 functions to hold the ratchet wheel against a reverse rotation. The carriage then continues its rotation and additional rearward steps are imparted to the racing figure each time the ratchet wheel engages the other two pawls of the set. The parts are so timed that the racing figures will all be moved rearwardly, step by step, during the cycle of operation whereby when the carriage is stopped all of the racing figures will be positioned at equal points at the rear of the carriage. During the cycle of movement, the several players manipulate the Bowden wires 95 so as to oscillate the

associated stop pawls and thereby endeavor to prevent said pawls from contacting the ratchet wheels. Consequently the racing figure of a player who employs the greatest skill will win the race because his racing figure will not be moved rearwardly relative to the carriage as far as the other racing figures. By employing the second stop arm 87 on each pawl, it will be apparent that considerable skill will be required by a player to avoid either one or both arms 86, 87 from being contacted by the ratchet wheel.

With the pawl 88 in its normal position, the ratchet wheel 73 will clear the stop arm 87 and contact the stop 86, causing the associated racing figure to be moved backward one step. However, if the pawl 88 is manually operated by the player before the ratchet wheel 73 has passed the stop arm 87, the wheel will contact the stop arm 87 and cause the associated racing figure to be moved rearwardly one step. If the player is skillful enough to effect this movement immediately following the passage of the ratchet wheel 73 over the stop arm 87, the ratchet wheel 73 will not contact either stop arm 87 or 86, thus allowing the associated racing figure to pass the pawl without any backward movement being imparted thereto. However, if the player should hold the pawl 88 in such a position as to leave the upper ends of the stop arms 87 and 86 in a horizontal plane, the ratchet wheel 73 will contact both stop arms 87 and 86 and thereby effect two backward movements of the associated racing figure of one step each. It will be apparent that the players will be assisted in the time for manipulating the Bowden wires by reason of the pawls being located immediately in front of the hurdles, and that the player who succeeds in rendering ineffective his holding pawl for the greatest number of times will become the winner because his racing figure will be moved rearwardly along the carriage for the least amount.

During the backward movements of the racing figures, the coil springs 76 will be wound and thereby tensioned for an amount sufficient to return said figures to the forward end of the carriage upon withdrawal of the back dogs 89 from the associated ratchet wheels. For this return of the racing animals to the forward end of the carriage at the conclusion of a race, I have provided manually operable means associated with the release arms 93 of said back dogs 89. This release means, as shown in Figure 4, comprises a horizontally disposed plate 106 which is located directly below said arms 93 and directly under the carriage when the latter is in a state of rest. Rigidly connected to the plate 106 and depending therefrom is a plurality of tubular legs 107 which normally rest on the base 5 of the casing. The plate 106 is adapted to be moved vertically into engagement with the lower ends 94 of the release arms 93. The plate is guided in its upward movement by means of upwardly extending posts 108 which are rigidly secured to the base 5 and project into the tubular legs 107. In order to elevate the plate 106, I have provided a cam lever 109 which is pivoted intermediate its ends as at 110 on a bracket 111 attached to the base 5. This lever 109 is actuated by a thrust rod 112 which extends rearwardly through the wall 6 of the frame and is provided with a fingerpiece 113 at its outer end. The thrust rod 112 passes through an opening in a bracket 114 fixed to the base 5 and a coil spring 115 is disposed around the rod between the bracket 114 and a stop pin 116 attached to

said rod. The spring 115 functions to yieldably urge the rod 112 outwardly so as to normally maintain the plate 106 in its lower position.

From the foregoing, it will be observed that whenever it is desired to release the back dogs 89 and restore the racing figures to their normal positions at the forward end of the carriage, the operator engages the fingerpiece 113 and pushes the thrust rod 112 inwardly against the tension 10 of the spring 115, thereby swinging the cam 109 and raising the plate 106 into engagement with the lower ends 94 of the release arm 93 of said back dogs.

Should another race be started without first restoring the racing figures to their initial starting positions at the front end of the carriage, it is possible that one or more of said figures will be at the rear end of the carriage. Therefore, if the carriage should be set in motion, the rear most racing figure would be automatically moved rearwardly by the pawl and ratchet means and cause the figure to abut the rear radial channel bar 25 of the carriage and thereby jam or break the mechanism. I have therefore provided an automatic means for avoiding this objection. This means comprises posts 117 fixed to the rear end of the carriage, there being one post for each figure. Each post is in position to be engaged by an arm 118 which extends laterally from the upper end of the tail 91 of the associated back dog 89 and thereby release the ratchet wheel 73 and gear 71 whereby the figure will be moved one step forwardly. Thus the figure will be intermittently moved forwardly and backwardly during the travel of the carriage and the danger of breaking the mechanism will be avoided.

From the foregoing, it will be observed that I have provided a carriage which is movable along a predetermined line; that means are provided for moving said carriage forwardly along said line; that a plurality of racing figures are mounted on said carriage for independent line movements relative thereto; that separate means are provided for respectively controlling the line positions of the racing figures on the carriage during the forward movement of the latter; that said separate means includes means for automatically and intermittently effecting rearward movements of the figures along the carriage and separate manually operable means for rendering ineffective said separate means during the carriage movement; that means are provided for automatically stopping the forward movement of the carriage at a predetermined point in the line of travel; that means are provided for effecting a return of all the figures on the carriage to their forward or initial positions, and that means are provided for preventing said figures engaging the rear end of the carriage during forward travel of the latter should the operator fail to restore the figures to their initial starting positions prior to the beginning of a race.

It is of course to be understood that the details of structure and arrangement of parts may be variously changed and modified without departing from the spirit and scope of my invention.

I claim:

1. In a racing game apparatus, the combination with a supporting element, of a carriage element movable along a predetermined line on said supporting element, means for moving said carriage element forwardly along said line, a plurality of racing figures mounted on said carriage element for independent line movements relative to the carriage element, separate means

mounted on said elements for automatically and intermittently effecting rearward movements of said figures along the carriage element during the forward movement of the latter, and separate manually operable means mounted on one of said elements for rendering ineffective said separate means during said carriage element movement.

2. In a racing game apparatus, the combination with a supporting element, of a carriage element movable along a predetermined line on said supporting element, means for moving said carriage element forwardly along said line, a plurality of racing figures mounted on said carriage element for independent line movements relative to the carriage element, said figures being initially located abreast at the forward end of the carriage element, separate means mounted on said elements for automatically and intermittently effecting rearward movements of said figures along said carriage element during the forward movement of the latter, means mounted on the supporting element for automatically stopping the forward movement of the carriage element at a predetermined point in said line, and separate means mounted on said elements and respectively connected to said figures and operable subsequent to the stopping of the carriage element for returning said figures to their initial abreast positions on the carriage element. 10 15 20 25

3. In a racing game apparatus, the combination with a supporting element, of a carriage element movable along a predetermined line on said supporting element, means for moving said carriage element forwardly along said line, a plurality of racing figures mounted on said carriage element for independent line movements relative to the carriage element, said figures being initially located abreast at the forward end of the carriage element, separate means mounted on said elements for automatically and intermittently effecting rearward movements of said figures along said carriage element during the forward movement of the latter, separate manually operable means mounted on one of said elements for rendering ineffective said separate control means during said carriage element movement, means mounted on the supporting element for automatically stopping the forward movement of the carriage element at a predetermined point in said line, and separate means respectively connected to said figures and operable subsequent to the stopping of the carriage element for returning said figures to their initial abreast positions on the carriage element. 30 35 40 45 50 55

positions on the carriage element, means mounted on the supporting element for normally retaining said separate returning means ineffective, and release means mounted on the supporting element and common to all of said retaining means.

5. In a racing game apparatus, the combination with a supporting element, of a carriage element movable along a predetermined line on said supporting element, said carriage element including a plurality of parallel rails extending longitudinally in the direction of travel of said carriage element, means for moving said carriage element forwardly along said line, a plurality of racing figures respectively mounted on said carriage element rails for independent line movements, separate means mounted on said elements for automatically and intermittently effecting rearward movements of said figures along said rails during the forward movement of the carriage element, and separate manually operable means mounted on the supporting element for rendering ineffective said separate means during said carriage element movement.

25. 6. In a racing game apparatus, the combination with a carriage movable along a predetermined line, said carriage including a plurality of parallel rails extending longitudinally in the direction of travel of said carriage, of means for moving said carriage forwardly along said line, said rails being respectively provided with rack teeth extending longitudinally therealong, a saddle mounted on each rail for longitudinal movements relative thereto, a racing figure mounted 30 on each saddle, said figures being initially located abreast at the forward end of the carriage, a gear wheel journaled on each saddle and engageable with the associated rack teeth, a ratchet wheel mounted to rotate with each gear wheel, a pawl 35 pivoted on a fixed axis and normally engageable by a tooth of the ratchet wheel during movement of the carriage to effect a backward movement of the racing figure relative to the associated rail, and separate manually operable 40 means respectively connected to said pawls for rendering the latter ineffective during movement of the carriage.

7. In a racing game apparatus, the combination with a carriage movable along a predetermined line, said carriage including a plurality of parallel rails extending longitudinally in the direction of travel of said carriage, of means for moving said carriage forwardly along said line, said rails being respectively provided with rack 50 teeth extending longitudinally therealong, a saddle mounted on each rail for longitudinal movements relative thereto, a racing figure mounted on each saddle, said figures being initially located abreast at the forward end of the carriage, a gear 55 wheel journaled on each saddle and engageable with the associated rack teeth, a ratchet wheel mounted to rotate with each gear wheel, a pawl pivoted on a fixed axis and normally engageable by a tooth of the ratchet wheel during movement 60 of the carriage to effect a backward movement of the racing figure relative to the associated rail, a coil spring associated with each gear wheel and arranged to be tensioned during said backward movement of the racing figure, a back dog 65 operating with the ratchet wheel to normally retain the spring under said tension, separate manually operable means respectively connected to said pawls for rendering the latter ineffective during movement of the carriage, means for 70 automatically stopping the carriage at a prede-

termined point in said line, and means operable subsequent to the stopping of the carriage for releasing all of said back dogs whereby the stored tensions of the springs will rotate the gear wheels and thereby return the racing figures to their initial abreast positions on the carriage.

8. In a racing game apparatus, the combination with a base, of a floor disposed above the base and having a plurality of spaced parallel slots, a hurdle located above and connected to the floor and positioned in operative relation to each slot, a carriage mounted on the base for movement along and below said slots, means for moving said carriage, a plurality of posts mounted on the carriage and projecting upwardly through said slots, racing figures mounted on said posts for vertical and pivotal movements relatively thereto whereby said figures will engage and travel over said hurdles, said posts being supported on the carriage for independent movements relative to the carriage and along the lines of the slots, separate means mounted on the carriage and base and located between the base and the floor for automatically and intermittently effecting rearward movements of said figures along the carriage during the forward movement of the latter, and separate manually operable means mounted on said base for rendering ineffective said separate means during said carriage movement.

25. 9. In a racing game apparatus, the combination with a casing including a plurality of endless tracks, of a carriage movable thereunder and supported in said casing, a plurality of racing figures independently mounted on the carriage for movements longitudinally thereof, an electric motor supported in the casing for moving said carriage along said tracks, a normally open switch located within and supported by the casing for controlling said motor, a push rod supported by the casing and operable externally thereof for closing said switch, a worm wheel located within and supported by the casing below the tracks and disposed concentrically of said tracks, said wheel being mounted on a vertical axis, a worm supported by the casing and operated by the motor for driving the worm wheel, a star wheel supported by and journaled within the casing and having a cam thereon, and a pin carried by the worm wheel for intermittently engaging and rotating the star wheel to thereby move the cam into engagement with the push rod and effect an opening of the switch.

10. In a racing game apparatus, the combination with a casing including a base, a surrounding wall, and a floor disposed above the base, said floor being provided with a plurality of endless tracks, of a carriage located below the floor and under the tracks and supported by the casing, means supported by the casing for moving the carriage along the tracks, a plurality of racing figures mounted on the carriage for independent movements longitudinally thereof, separate means located within the casing and below the floor and supported by the carriage and the casing for automatically and intermittently effecting rearward movements of the figures along the carriage, and separate means mounted on the carriage and located therein below the floor for rendering ineffective said separate automatic means during the carriage movement and manually operable exteriorly of said casing.

11. In a racing game apparatus, the combination with a casing including a base, a surrounding wall, and a floor disposed above the base, said floor being provided with a plurality

of endless tracks, of a carriage located below the floor and under the tracks, an electric motor located on said floor for moving the carriage along the tracks and supported by the casing, 5 a normally open switch located within and supported by the casing below the floor for controlling said motor, means mounted on the casing and operable exteriorly thereof for closing the switch, a plurality of racing figures mounted on 10 the carriage for independent movements longitudinally thereof, separate means located within the casing and below the floor and supported by the carriage and the casing for automatically and intermittently effecting rearward movements 15 of the figures along the carriage, separate means mounted on the casing and located therein below the floor for rendering ineffective said separate automatic means during the carriage movement and manually operable exteriorly of said casing, 20 and means supported on the casing and operable by the motor for automatically opening the switch upon travel of the carriage for a predetermined distance.

12. In a racing game apparatus, the combination with a support, of a carriage movable along a predetermined line on said support, means mounted on the support for moving said carriage forwardly along said line, a plurality of racing figures 25

mounted on said carriage for independent line movements relative to the carriage, separate means mounted on the support and carriage for automatically and intermittently effecting rearward movements of said figures along the carriage 5 during the forward movement of the latter, separate manually operable means mounted on the support for rendering ineffective said separate means during said carriage movement, and means mounted on the carriage for automatically reciprocating the racing figures on the carriage when said figures are at the rear end thereof. 10

13. In a racing game apparatus, the combination with a supporting element, of a carriage element movable along a predetermined line on said supporting element, means for moving said carriage element forwardly along said line, a plurality of racing figures mounted on said carriage element for independent line movements relative to the carriage element, separate means mounted on said elements for automatically and intermittently effecting movements of said figures along the carriage element during the forward movement of the latter, and manually operable means mounted on one of said elements for rendering ineffective said separate means during said carriage element movement. 15 20 25

ARLEY L. KEITH.
